Louis A. Lupien,
BY
Mark J. Kent
ATTORNEY

UNITED STATES PATENT OFFICE.

LOUIS A. LUPIEN, OF BROOKLYN, NEW YORK, ASSIGNOR TO EDWIN B. STIMPSON COMPANY, OF BROOKLYN, NEW YORK.

FASTENER.

Application filed February 7, 1924. Serial No. 691,136.

To all whom it may concern:

Be it known that I, LOUIS A. LUPIEN, a citizen of the United States, residing at Brooklyn, in the county of Kings and State 5 of New York, have invented certain new and useful Improvements in Fasteners, of which the following is a specification.

This invention relates to head coverings in which provision is made for varying the 10 size of the headband, and the objects of the invention are to provide simple, practical inexpensive and easily applied means by which these adjustments can be quickly made and which will automatically lock 15 and be retained in adjusted relation.

These objects are attained by certain novel 20 features of construction, combinations and relations of parts as will be clear from the following specification.

The drawing accompanying and forming 25 part of the specification illustrates the invention embodied in several different forms and it should be understood that the structure may be further varied without departure from the true spirit and scope of the 30 invention as hereinafter defined and claimed.

Figure 1 is a front view of a cap showing 35 one form of the invention applied thereto. Figure 2 is a longitudinal sectional view of the adjustable clasp construction as taken on substantially the plane of line 2-2 of 40 Figure 1.

Figures 3-4, 5-6 are sectional and front 45 views respectively of modified forms of the clasp construction.

The cap or head covering may be of any 50 usual or special construction, except that it has a head-band 15 which is adjustable 40 by means of the overlapping tabs 16, 17 provided at the front of the cap and carrying the cooperating parts of an adjustable clasp.

All of the several forms of clasps shown 55 are alike in that they each consist of a keeper plate 18 secured to one of the tabs provided with seats or openings 19 to receive a projecting hook or tongue 20 carried by a plate 21 attached to the other tab.

In the first form of the invention disclosed 60 the keeper plate is made with raised beads or shoulders 22 about the rims of the adjustment openings 19 and the shank of the hook 20 is made with a depression 23 which snaps over these beads when the hook 65 is engaged in the openings, as indicated in

Figure 2, to operate as a spring lock yieldingly retaining the parts in adjusted relation.

The structure of Figures 3 and 4 is similar to the first form with the clasp having 60 in addition to the spring interlock, a positive interlock in the form of lugs 24 turned inward at the opposite edges of the hook plate 21 and cooperating with properly spaced holes 25, in the upper and lower 65 edges of the keeper plate. As will be clear from Figure 3, before this form of catch can be released, the base of the hook must be pulled away from the face of the keeper plate to release the lugs 24 from the holes 70 25 and then the hook can be shifted longitudinally to spring it out of the opening in which it is engaged.

The structure of Figures 5 and 6 is like 75 that just described except that the additional locking points 24^a are carried at the ends of spring fingers 26 extended from the forward edge of the plate 21. With this construction it is simply necessary to apply sufficient endwise pressure to the hook to 80 force the spring tongues out of the holes 25 and to overcome the holding tension of the spring hook.

In all the forms of the invention the 85 adjustments are quickly and easily effected and when the adjustment is made, the parts are automatically locked by a spring snap action and will stay so until purposely released. The desirable features of simplicity and low cost are also present in the various 90 forms of the invention.

What I claim is:

1. A fastening device comprising a keeper plate having adjustment openings therein and upstanding shoulders surrounding the 95 rims of such openings and a hook engageable in said openings having a shank with a depression therein to snap over in back of such shoulders when the hook is engaged in the openings.

2. A fastening device comprising a keeper plate having adjustment openings therein and upstanding shoulders surrounding the rims of such openings and a hook engageable in said openings having a shank with a depression therein to snap over in back of such shoulders when the hook is engaged in the openings, the keeper plate having openings at the sides of the hook receiving openings and the hook member carrying inwardly 100 105 110

extending lugs engaging in the latter openings to retain the shank of the hook sprung in engagement with the shoulders.

3. A fastening device comprising a keeper plate having adjustment openings and locking openings at opposite sides of the adjustment openings and a hook engageable in the adjustment openings and having a shank, inwardly extending lugs at opposite sides of the hook shank engageable in the locking openings to secure the hook against longitudinal disengagement from the adjustment openings and to prevent twisting of the hook with respect to the keeper plate.

10 4. A fastening device comprising a keeper

plate having adjustment openings and locking openings at opposite sides of the adjustment openings and a hook engageable in the adjustment openings and having a shank, inwardly extending lugs at opposite sides of the hook shank engageable in the locking openings to secure the hook against longitudinal disengagement from the adjustment openings and to prevent twisting of the hook with respect to the keeper plate, the locking lugs being carried by independently yielding spring fingers located at opposite sides of the hook.

20 25 In testimony whereof I affix my signature.

LOUIS A. LUPIEN.
